UNITED STATES PATENT OFFICE.

YVES PAUL GASTON LE PRIEUR, OF PARIS, FRANCE.

APPARATUS FOR CORRECTING THE COURSE ON BOARD AEROPLANES.

Application filed June 6, 1921. Serial No. 475,489.

(GRANTED UNDER THE PROVISIONS OF THE ACT OF MARCH 3, 1921, 41 STAT. L., 1318.)

To all whom it may concern:

Be it known that I, YVES PAUL GASTON LE PRIEUR, a citizen of the French Republic, residing at 61 Rue Pernety, Paris, France, have invented certain new and useful Apparatus for Correcting the Course on Board Aeroplanes (for which I have filed an application for patent in France on June 5, 1921, No. 517,904), of which the following is a specification.

When a pilot is engaged in making preparations to travel with an aeroplane from one point to another, he draws upon the map a straight line connecting the two points and then measures the direction of this line. Should there be no wind prevailing at the time, it would be sufficient to maintain the aeroplane upon this course as indicated by the compass, this latter being corrected for any inherent errors if required. But in practice the action of the wind constitutes a very appreciable influence in modifying the course followed by the aeroplane, thus introducing a factor of uncertainty into the estimate of the position of the aeroplane, and this becomes still more considerable when the speed and direction of the wind are subject to frequent changes. For a given speed of the wind, the actual speed of the aeroplane with reference to the ground is both in magnitude and direction the resultant of the air speed of the aeroplane in calm air and the speed of the wind.

These three speeds form a triangle, and the angle made by the center line of the aeroplane with the route followed along the ground is termed the angle of drift. Should it be desired to obtain a correct course, the pilot may be enabled to determine the compass point to be used for steering at each instant whereby this result may be obtained, he is consequently required to know the speed of the wind. This speed may be deduced, as will be set forth hereunder, from the measurement of the angle of drift which is made by the pilot during the travel of the aeroplane by observing the direction of movement of visible points on the ground with reference to the center line of the aeroplane.

The path rectifying apparatus according to my invention permits determining the speed of the wind by causing the aeroplane to successively follow two courses on different points of the compass, and in measuring

the angle of drift corresponding to each of the said courses.

The accompanying drawings show by way of example, various constructional forms of my correcting apparatus.

In the drawings:

Figure 1 is a plan view of the correcting apparatus with a drift meter on the gyroscope principle.

Fig. 2 is a longitudinal section in elevation of the said gyroscope drift meter on the line X—X of Fig. 1.

Fig. 3 is a diagrammatic view illustrating the graphic method for measuring the drift.

Fig. 4 is a graphic diagram of an observation as obtained upon the board.

Fig. 5 shows in perspective the first constructional form of the recording device comprising an articulated parallelogram.

Fig. 6 is a diagrammatic view illustrating the operation of the same.

Fig. 7 shows the use of the graphic diagram obtained by the said drift-meter in the apparatus shown in Fig. 1.

Fig. 8 is a diagrammatic view showing a second constructional form of the graphic diagram apparatus constituted by a camera.

Fig. 9 is a diagrammatic view illustrating the graphic method in the case where the observations are transferred to a vertical board.

Fig. 10 represents the latter board with the diagram of an observation.

Figs. 11 and 12 show in perspective two graphic diagram devices, whereof one is provided with an articulated parallelogram and the other with a camera, for the use of the said vertical diagram.

Fig. 13 is a view of the assembled route rectifier installed in the keel of an aeroplane.

The path rectifying apparatus (Fig. 1) comprises a small board 1 disposed before the observer and having mounted thereon the toothed disk 2 which is revoluble about its shaft 3. The disk 2 carries a graduated scale which is the same as the compass scale. The said disk is provided with a plane table 4 whereon may be secured a sheet of paper 5 by means of the hoop 6 which is adapted to fit upon the edges of the paper in order to maintain the same. The sheet or chart 5 carries a set of parallel lines. The plane table 4 carries the reference line 7, and the ruled chart is so disposed that its lines shall

be parallel to this line 7. The toothed disk 2 rotates before a stationary pointer 8 which is situated upon the center line of the aeroplane and is actuated by a worm 9; this latter is connected through a flexible transmission device 10 in such manner as to produce like movements of a repeating disk 11 revoluble about its center 12 upon a small board 13 and in front of the pointer 14. 5 This latter disk is disposed before the pilot and beside the steering compass. At the point 15 of the board 1 and in the same longitudinal plane as the center 3 and the pointer 8 at a distance from the center representing the speed of the airplane in calm air, is pivoted the apparatus known as "drift-meter" upon a vertical axis, this being a sighting apparatus operating according to a vertical sighting plane 17. The 10 ruler 18, which is secured to the said drift-meter 16, is disposed parallel to the sighting plane and the inner edge thereof is caused to pass through the point 15, the ruler thus moving over the chart 5 to correspond with the movements of the drift-meter.

This apparatus is employed in the following manner: If it is supposed that the geographical course to be followed is for instance due north, the aeroplane will start 15 out on its course according to the north point of the compass; should it be submitted to the action of a wind having the speed V , it will follow in reality another route with reference to the ground. The chart 5 is 20 disposed upon the plane table 4 in such manner that its set of parallel lines shall be situated in the direction of the reference line 7, and the plane table 4 has been so disposed upon the graduated disk 2 that its 25 reference line 7 shall be located opposite the graduation corresponding to the geographical course to be followed, or the north in the present case.

The graduated disk 2, which is used by 30 the observer in order to transmit his indications for the route to the pilot by means of the repeating disk 11, is constantly directed in the same manner as a compass card if the pilot controls correctly by following the graduations of the repeating disk, that is, the chart 5 is always properly directed in space, the reference line 7 and the set of parallel lines being directed towards the geographical north.

35 While the aeroplane is holding the actual course (Fig. 4), the observer measures an angle of drift a by so disposing the ruler 18 that a chosen visible point on the ground shall be seen to pass along the sighting plane 40 17 of the drift-meter 16. He then draws a line Y upon the chart, whereupon he directs the course on a compass line which is quite different from the first one, for example N. 60° W., bringing the corresponding 45 direction of the graduated disk 2 opposite the

pointer 8, thus transmitting the necessary indication to the pilot.

He thereupon makes a second measurement of an angle of drift a' and uses the ruler 18 to draw upon the chart 5 the line Y' . The two lines Y and Y' will intersect at a point 19 which gives the extremity of the line representing the speed of the wind AB to the same scale upon which the air speed of the aeroplane is represented by the 75 distance from the center 3 to the pivot 15 of the drift-meter.

To determine the course according to the compass which is to be employed for the aeroplane in order that it shall be made to follow the actual direction along the ground, that is, due north, the worm 9 is operated in order to bring the reference line 7 of the plane table and the set of lines of the chart 5 parallel to the ruler 18 at the same time that the said ruler shall pass through the point 19, this being the position shown in Fig. 1. The compass point of the course to be followed is now the one which is indicated by the division of the graduated circle 90 2 which is opposite the pointer 8, and inasmuch as this division is reproduced by the disk 11 opposite the pointer 14, the pilot will therefore steer the aeroplane according to the new course which is indicated. This 95 compass will cause the aeroplane to follow along the ground or the route due north, which is the correct route to be followed. The angle of drift for this route is the angle made by the ruler 18 in the position 100 shown in Fig. 1 with reference to the center line of the aeroplane. The observer verifies from time to time that the drift-meter when in this position will in fact correspond to the actual drift, and should he note any appreciable change in the drift, he will make new measurements by the method above indicated in order to determine the new course to be followed according to the compass 105 such as enable him to return to the veritable and correct route under the new conditions of the wind.

The drift-meter which is shown in Fig. 2 comprises a casing 20 provided in the interior with a pivot 21 having revoluble thereon a gyroscope disk 22 of the known type which has the property of maintaining its axis in the vertical position irrespectively of the inclination and other movements of its support. The rotation of the said gyroscope is effected for instance in a continuous manner and by the use of a device which is not necessary to indicate, which acts by means of air currents introduced through suitable apertures in the casing 20 admitting the outer air to a set of blades carried on the periphery of the gyroscope 22, the air being drawn in by means of a tube 23 connected with a suitable suction device such as a venturi which 115 120 125 130

is adapted to produce a vacuum within the casing 20. The gyroscope 22 has mounted thereon a collimator 24 comprising a lens 25 and a slit 26 disposed at the focus thereof and forming an optical system whose axis is perpendicular to the axis of the gyroscope and is therefore invariably in the horizontal position during the rotation of the gyroscope. The lighting is obtained by 5 a lamp 27 situated at the focus of a lens 28 which is disposed within the casing 20. On the opposite side of the said casing and rearwardly of the aperture 29 is disposed a pentagonal prism 30 which is secured in 10 the casing 20, the said prism being of the known type wherein the rays entering at the face 31 are submitted to two total reflections and pass out through the face 32 in a direction exactly perpendicular to their 15 original direction.

The operation of the said drift-meter is as follows: When the gyroscope is in rotation its axis will remain in the vertical position, and the rays passing through the collimator 24 will form an image of the slit 26 in a plane which is invariably horizontal. The light beam passing through the aperture 29 will form outwardly of the pentagonal prism 30 the image of the slit 30 at an infinite distance, and whose vertical position remains unaffected by jarring movements or the pitching or rolling of the aeroplane. The eye placed at 33 in the path of the beam will perceive a luminous 35 line which is in an absolutely fixed position and appears projected upon the ground, this latter being also observed by the other eye by direct vision. Under these conditions, it is an easy matter to so direct the 40 drift-meter that a given visible point on the ground shall be seen to pass along in the vertical plane of sighting and along the said luminous line. This disposition enables the measurement of the angle of drift 45 to be carried out in a very easy and exact manner, provided the aeroplane has no zig-zag or yawing motion.

The ruler 18 is provided with a scale graduation in speeds, the length 15-3, or 50 O' A' being taken as unity. The point on the said ruler upon which is projected the point of intersection 19 of the two lines Y Y' indicates the speed with reference to the ground, taking as unity the air speed 55 of the aeroplane in calm air, that is, it indicates the coefficient by which the latter, which is a known quantity, is to be multiplied in order to obtain the former.

The graphic method used for the measurement of an angle of drift as well as the corresponding apparatus are set forth as follows:

Considering as in Fig. 3 an aeroplane 101 having an air speed represented by the arrow 102 and traveling in reality at the

speed represented by the arrow 103 by reason of the action of the wind; tracing upon the ground 104 the line 105 constituting the projection of the line of travel of the aeroplane, this line will represent the actual course of the aeroplane with reference to the ground. The movement of the aeroplane with reference to the ground is the same as if the aeroplane were considered as fixed in space and the ground as moving 70 in the contrary sense at the speed represented by the arrow 103'. Under these conditions a given point on the ground 106 will move along a line parallel to the arrow 103'. Should this point 106 be followed 75 from the aeroplane by means of a sighting line and should the path of this line be marked upon a horizontal board 108 carried upon the aeroplane, there will be obtained, starting with the point 106' or the record 80 of the first sighting operation on the board 108, a line 109 which is parallel to the actual route of the aeroplane with reference to the ground. Whatever may be the point chosen, provided the compass course of the 85 aeroplane and the wind remain unchanged, the records of all the sighting operations on different points of the ground which are made upon the board 108 will be parallel lines. The angle made by these lines with 90 the centre line of the aeroplane represented by the arrow 102 will constitute the angle 95 of drift.

But as a matter of fact, the aeroplane will not preserve an invariable direction in space 100 by reason of the difficulty encountered in following the course according to the compass, and it is furthermore submitted to pitching and rolling motion whereby the successive lines of sighting on a given point 105 will no longer be located in the same plane, but will more or less depart therefrom by reason of such accidental movements. For this reason the path 109 of the sighting line of the point 106 upon the observation board 108 will no longer be a straight line, but an irregular undulated line 110 as shown in Fig. 4. But this undulated line 110 will have a well-determined general direction 111 which may be readily marked out 115 and will be exactly parallel to the actual line of speed of the aeroplane with reference to the ground. This graphic method of measuring the angle of drift will eliminate the accidental errors by giving the mean of 120 a considerable number of observations.

In the first constructional form of apparatus for the application of this graphic method as shown in Fig. 5, the apparatus is mounted upon the support or base 112 perpendicular to the board 108 which as stated is disposed horizontally in the aeroplane when in normal position of flight. The upright 112 has disposed thereon a horizontal tube 113 having pivoted thereto the lower 125

member of an articulated parallelogram, the sides whereof are provided respectively at 115 with a sighting device and at 116 with the pencil 117 adapted to bear upon the 5 paper or chart of the board 108. By reason of this disposition, the two opposite sides 115 and 116 will remain invariably parallel, and the line of sight 115 is susceptible of assuming all required positions in space for 10 the purpose of sighting and following any desired point. Should this sighting line 15 (Fig. 6) be used to follow the movements of a given point on the ground, the pencil 117 will draw upon the chart 108 a line 111 15 corresponding to the line 111' representing the movement of the said point on the ground with reference to the aeroplane, and by observing various points the result will be a set of lines such as 108'. 20 This latter set of lines is used in the device hereinbefore described and shown in Fig. 1, as indicated in Fig. 7. The board 108 may be given a displacement perpendicular to the center line of the aeroplane 25 whereby it shall be caused to pass from the position of observation below the pencil 117 Fig. 6 to the position of use Fig. 7. As hereinbefore set forth, the course-correcting device 120 is provided with a ruler 121 for 30 producing the required geometrical plan. The said ruler is provided with an extension arm 122 movable over the sheet of paper 108, and the said arm is to be directed according to the measured angle of drift; 35 for this purpose it is made to coincide with the mean direction of the lines of the chart 111.

In Fig. 8 is shown a second constructional 40 form of device for producing the drift-meter chart, which comprises a camera 123 provided with a lens or an aperture 124 and screen which is horizontal under normal conditions of flight. A point on the ground 126 will produce its image at 126', and when its 45 relative movement brings it to the point 127, the image will now have moved to the point 127'. By inscribing upon the screen 125 all the positions of this image, the result will be a sinuous line similar to the lines shown in 50 Fig. 4.

The observation diagram may likewise be 55 made upon a vertical board disposed perpendicular to the center line of the aeroplane, and in this case the operation is represented diagrammatically in Fig. 9. The aeroplane 128 moves above the ground 129, the actual displacement being along the line 130. Observation is made of the relative movements of a point 131, and the direction of the line of sight is inscribed upon 60 a vertical board 132 carried upon the aeroplane and disposed perpendicular to the center line of the same. This will afford at 131 the record of the observation 128-131. 65 When the point 131 moves upon the line

parallel to 130, the image of this point 131' moves upon the board 132 according to a straight line which passes through the vanishing point 133 of the direction line 130. This vanishing point is determined as is 70 well known by a line passing through the point of observation 128 and parallel to the actual movement 130 of the aeroplane with reference to the ground. The same vanishing point is likewise situated upon the horizon line 134 of the observation point 128. All that is necessary is to take the intersection of the line drawn upon the board 132 during the sighting operation with the horizon line 134, in order to obtain the vanishing point 133 and to be enabled to draw the line 128-133 from the vanishing point and to measure the angle between this line and the center line of the aeroplane, that is 75 80 85 the angle of drift.

By making successive observations of a certain number of points 131-135, Fig. 9, this will produce various lines upon the board 132, and all of the said lines should intersect the horizon line 134 at the same 90 point. In this manner a mean position may be taken if the concordance is not exact.

This method of observation upon a vertical board may be used when the points on the ground situated below the aeroplane are 95 not visible for any reason, for instance in the presence of clouds, but where the horizon is clear and may be thus observed. As concerns the effect of the accidental movements 100 of the aeroplane upon the observation diagram, the same indications will hold good which have been herein set forth in the case the diagram formed upon the horizontal board, and the result will be as shown in 105 Fig. 10. A certain number of sinuous lines 136 will thus be obtained upon the board 132 whose mean direction line will coincide in the vanishing point 133 located on the horizon line 134. The distance from 110 this point 133 to the longitudinal plane of the aeroplane passing through the observation point and whose record is shown at 137 will afford the measurement of the angle of drift. The vertical board 132 may be disposed either forwardly or rearwardly of the 115 observer. In the former case the successive points of a given observation will descend below the horizon line 134, and in the latter case they will rise towards this line.

In the apparatus shown in Fig. 11, upon the board 120 provided with the above-mentioned members is disposed an upright support 138 having pivoted thereto at 139 and upon a horizontal axis perpendicular to the longitudinal plane of the aeroplane, an articulated parallelogram whose upper arm 140 is provided with a sighting device and whose lower arm is provided with a pencil 142. Upon the board 132 are drawn the records of observations as shown by the sinuous 120 125 130 135 140

lines 136, and the mean directions of the same will intersect at the vanishing point 133 located on the horizon line 134. The movement which is made in order to bring 5 the point of the pencil to 133 will effect a parallel movement of the ruler 121 and this latter will be thereby directed according to the angle of drift, in such manner that the desired geometrical diagrams may immediately be produced.

10 In the apparatus shown in Fig. 12 the diagram is formed upon a vertical screen constituting the rear portion of a camera 144. When the vanishing point 133 has been obtained 15 as before, the ruler 120 is brought upon the bottom of the vertical line passing through this point 133 in order to carry out the desired geometrical constructions. The board which is disposed upon the aeroplane 20 for drawing the lines corresponding to the sighting operations may be given another direction than the vertical or horizontal, and the angle of drift may be ascertained in all such positions; however, this operation 25 is particularly simple in the two cases herein mentioned.

Fig. 13 shows the assembled route rectifier, installed in the nacelle of an aeroplane. 30 150 designates the compass and 151 the body of the aeroplane. The route rectifying apparatus is placed in front of the seat of the observer 153 and the order transmitting disk 13 is placed in front of the seat of the pilot 154. 152 is an opening provided in the bottom 35 of the nacelle to permit the ground to be observed by means of the sighting member 115.

Having now particularly described and ascertained the nature of my said invention 40 and in what manner the same is to be performed, I declare that what I claim is:

1. The combination with an aeroplane and a compass on said aeroplane, of an aeroplane path rectifying device comprising a fixed horizontal board, a graduated disk rotatable on said board and having graduations identical with graduations of the compass, means to direct said disk like the compass, a sighting device carried by the said board, a rule pivoted on a vertical axis located in the same longitudinal plane of the aeroplane as the center of 45 50 55 60 65 70 75 80 85 90 95 100 the above disk and at a distance from the center representing the air speed of the aeroplane, and means to direct said rule parallel to the sighting plane of the sighting device.

2. The combination with an aeroplane and a compass on said aeroplane, of an aeroplane path rectifying device comprising a fixed horizontal board, a graduated disk rotatable on said board and having graduations identical with graduations of the compass, means to direct said disk like the compass, a sighting device carried by the said board, a rule pivoted on a vertical axis located in the same longitudinal plane of the aeroplane as the center of the above disk and at a distance from the center representing the air speed of the aeroplane, a sighting device carried by the said board, a sighting inscription member combined with the said sighting device for tracing on a horizontal plate lines substantially parallel to the sighting plane, and means to direct the rule along the said lines.

3. The combination with an aeroplane and a compass on said aeroplane, of an aeroplane path rectifying device comprising a fixed horizontal board, a graduated disk rotatable on said board and having graduations identical with graduations of the compass, means to direct said disk like the compass, a sheet marked with parallel lines on said disk, a second disk repeating the movement of the said disk, a vertical column supporting a horizontal sleeve, a pivoted parallelogram whose lower side is engaged in said horizontal sleeve, a sight line on one of the small sides of the parallelogram and an inscribing stylus on the opposite side, a horizontal plate movable perpendicular to the axis of the aeroplane and adapted to be first placed under the stylus opposite the rotatable disk and a horizontal rule pivoted on a vertical axis located in the same longitudinal plane of the aeroplane as the center of the rotatable disk and at a distance from the center representing the air speed of the aeroplane and provided with an extension below which the above said plate is placed.

In witness whereof I have hereunto set my hand.

YVES PAUL GASTON LE PRIEUR.
